UNITED STATES PATENT OFFICE.

CHARLES F. BIELE, OF NEW YORK, N. Y.

MOLDING.

SPECIFICATION forming part of Letters Patent No. 289,606, dated December 4, 1883.

Application filed September 26, 1883. (Model.)

To all whom it may concern:

Be it known that I, CHARLES F. BIELE, of the city, county, and State of New York, have invented certain new and useful Improvements in Moldings, of which the following is a specification.

This invention has reference to the manufacture of ornamental moldings for show-cases and other articles.

10 Figure 1 is a front view of my improved molding, and Fig. 2 is a cross-section of the same on line *x x*, Fig. 1.

Similar letters of reference indicate corresponding parts.

15 *a a* represent panels, which are formed of mother-of-pearl, and cemented to the face of a molding, *b*, of a suitable cross-section. The molding *b* is made of wood or other suitable material, and when of larger size made of several connected sections. After the panels of 20 different shapes have been cemented to the face of the molding according to a certain design, they are ground off on their faces to a uniform thickness, and also at their meeting edges, so as to form proper joints with the

adjoining sections of the molding. If the molding is composed of several sections, they are connected by a tongue-and-groove joint, dovetails, mortises, and tenons, or in any other suitable manner.

30 Moldings which are faced in this manner with mother-of-pearl can be made in different artistic designs, and impart thereby a very ornamental effect to the show-cases, frames, or other articles for which they are used.

35 Having thus described my invention, I claim as new and desire to secure by Letters Patent—

The article of manufacture herein described, 40 consisting of a molding having polygonal faces covered with panels of mother-of-pearl, the meeting edges of the panels being beveled.

In testimony that I claim the foregoing as my invention I have signed my name in presence of two subscribing witnesses.

CHARLES F. BIELE.

Witnesses:

PAUL GOEPEL,
SIDNEY MANN.
